VACUUM DOUBLE SEAMING MACHINE

Henry L. Guenther, Los Angeles, Calif.

Application March 3, 1939, Serial No. 259,528

11 Claims. (Cl. 113—24)

This invention relates to can sealing machinery and particularly pertains to a vacuum double seaming machine.

In the canning industry it is desirable to seal various products within double seaming machines under vacuum. In performing this operation it develops that various problems are present which require special attention in their solution. One of these problems has been to provide a vacuum double seaming machine through which filled cans may be moved at a relatively high rate of speed and in which machine the cans will be sealed by a rapid and effective double seaming operation. It has also been found desirable to provide simple means by which the cans are introduced into a vacuum chamber without breaking the vacuum seal within the chamber and while insuring that the introduced can and its contents will be subjected to a suitable vacuum prior to and during the double seaming operation, and that the can may afterwards be ejected from the vacuum chamber without breaking the vacuum. In this type of machinery it has also been ascertained that there is a tendency for the machine to overheat and it is desirable to properly lubricate and cool the machine so that it may function at high speed. Furthermore, it is often necessary to seal cans of various height and diameters which usually require the provision of separate machines to accommodate different sized cans.

It is the principal object of the present invention to provide a vacuum double seaming machine to and from which the cans may be moved through valve structures of simple form and operation, whereby the vacuum chamber will be maintained sealed even while the cans are being introduced and removed from the chamber, and in which vacuum machine various adjustments are provided to readily adapt the machine to use with cans of different sizes and to furthermore provide a vacuum closing machine which has simple and effective cooling means, lubricating means and other refinements and details of construction of a novel character whereby vacuum sealing of cans may be carried on efficiently at a high rate of speed and with a desired degree of vacuum action.

The present invention contemplates the provision of a can double seaming machine embodying the use of valves for the inlet and outlet of cans to a vacuum chamber, the said valve structures being novel in design and insuring proper delivery of cans and caps to the vacuum chamber and the withdrawal of the sealed cans from the

vacuum chamber without loss of vacuum, the structure embodying adjustable turrets and an adjustable frame structure whereby the height of different cans may be accommodated and the structure also embodying a lubricating and cooling system for the operating mechanism in the vacuum chamber, whereby wear of the parts will be eliminated and high speed action may be obtained.

The invention is illustrated by way of example in the accompanying drawings, in which:

Fig. 1 is a view in side elevation showing a form of the vacuum machine with which the present invention is concerned, and having horizontally swinging valve units and a rigid base.

Fig. 2 is a view in side elevation showing the form of the invention in which the can valve is vertically adjustable with relation to the housing and in which the base of the housing is vertically adjustable.

Fig. 3 is a view in plan showing the form of the invention disclosed in Fig. 1 of the drawings.

Fig. 4 is an enlarged view in vertical section and elevation showing a can valve unit of the type particularly disclosed in Fig. 2 of the drawings and indicating in detail the means for vertical adjustment.

Fig. 5 is a view in central vertical section as seen on the line 5—5 of Fig. 3 disclosing the double seaming turret within the housing and the method of adjusting the seaming heads with relation to the seaming chucks.

Fig. 6 is an enlarged view in transverse section as seen on the line 6—6 of Fig. 5.

Fig. 7 is an enlarged view in section and elevation similar to that disclosed in Fig. 6 but showing the details of construction of a feed valve with greater particularity.

Fig. 8 is a view in diagram showing the flow plan of the machine.

Fig. 9 is a view in diagram showing the gear train of the vacuum seaming unit and the valves.

Fig. 10 is an enlarged fragmentary view in vertical section showing the leg structure on the type of machine disclosed in Fig. 2, whereby the height of the machine may be controlled.

Fig. 11 is an enlarged view in central vertical section showing the type of can valve indicated particularly in Figs. 1 and 3 of the drawings and in which the valve structure swings horizontally.

Fig. 12 is a view in horizontal section as seen on the line 12—12 of Fig. 11 and discloses the driving engagement of the drive shaft for the can valve turret.

Fig. 13 is a fragmentary view in central section

showing the interlocking safety clutch structure.

Fig. 14 is a view showing the vertical adjustment control mounted upon the lower turret of the double seaming unit.

5 Referring more particularly to Fig. 8 of the drawings it will be seen that two units are shown, an initial seaming unit 10 and a final vacuum seaming unit 11. The flow of cans is delivered from a suitable can run and on to the feed disc 10 12, after which the cans pass along and between the guide rails 13 and 14 and on to a feed disc 15. The cans then pass around and between guide rails 16 and 17 and into the arcuate run 18, where they are delivered to the first seaming station 15 represented by the initial double seaming unit 10. At this station the cans pass into a rotary turret 19 where they are carried around the axis of a shaft 20 and during which time an initial seaming operation or clenching operation may be performed to produce a preliminary assembly of the can body with the can cap. Seaming heads 21 are generally indicated in the drawings, it being understood that these seaming heads may be of any desired construction but preferably of the type shown in my U. S. Letters Patent No. 2,052,620 issued to me on the 1st day of September, 1936. When the cans leave the turret 19 they are engaged by the feed fingers 22 mounted upon a shaft 23 and then move along and around 20 the guide rail 24 to a transfer disc 25. This disc delivers the cans on to a feed plate 26 of the vacuum seaming unit 11. Feed fingers 27 mounted upon a shaft 28 receive the cans and successively feed them into the inlet feed valve 29.

35 The construction of the inlet feed valve is more particularly disclosed in Figs. 4 and 7 of the drawings. Here it will be seen that an arcuate guide rail 30 is provided which is concentric with the axis of the shaft 28 and which shaft is mounted in a suitable bearing bracket 31. The bearing bracket 31 is carried by the cylindrical valve housing 32 and is secured by suitable cap screws 33. The bearing bracket also carries guide fingers 34 which cooperate with the guide rail 30 to form 40 a throat through which the cans, generally indicated at 35, pass while entering the housing 32. The inlet valve housing 32 is provided with an inlet opening 36 to receive the cans and an outlet opening 37 through which the cans are ejected 45 into the main housing 38 of the vacuum chamber 39 within which the cans are vacuum sealed.

50 Extending vertically through the housing 32 is a shaft 40. This shaft is mounted at its upper end within an anti-friction bearing 41 carried by 55 the cover plate 42 of the valve housing. The cover plate 42 is provided with a central bore 43 to receive the bearing 41 and is fitted with a packing gland cap 44 at the lower end of the bore and around the shaft 41 while the upper 60 end of the bore is closed by a cover 45. Bolts 46 are provided to secure the members 44 and 45 in assembled position at opposite sides of the member 42 and the bearing 41. A suitable space for grease is thus formed and a lubricant may be 65 introduced through a member 47.

The shaft 40 is also mounted in a lower bearing including an anti-friction bearing element 48 which is carried in a central bore 49 of a lower spider 50. This spider is secured in position by 70 cap screws 51. An upper packing cup 52 is secured over the bearing 48 and is held in its assembled position by bolts 53. These bolts also pass through the flange of a threaded adjusting sleeve 54 which extends downwardly around a lower reduced ends of the shaft 40. Mounted over

75 the threaded adjusting sleeve 54 is an outer sleeve 55 which is threaded on to the sleeve 54 and is provided with bosses 56 to receive a spanner wrench by which the outer sleeve may be rotated. The threaded portion of the outer sleeve is indicated at 57, where it will be seen to extend only a portion of the length of the bore of the sleeve, the remaining lower portion of the outer sleeve being counter-bored. The outer diameter of the outer threaded sleeve is externally threaded as 10 indicated at 58 and engages a threaded portion 59 of a tubular standard 60. The tubular standard 60 is fastened to a horizontal portion 61 of the main housing of the seaming machine by cap screws 62. By this arrangement rotation of the 15 outer sleeve 55 will adjust the outer sleeve with relation to the standard 60 and the inner sleeve 54 so that the bearing structure 48, the member 50 and the valve housing 32 with all of its enclosed parts may be raised and lowered bodily 20 for the purpose of adjustment, as will be hereinafter described.

25 Mounted within the valve housing 32 is a turret 63. This structure is formed with a central hub 64 which is keyed on to the shaft 40 and which carries an upper circular disc 65 and a lower circular disc 66. The two discs are cast integral with the hub 64 and are disposed parallel to each other. The discs are recessed, as indicated by dotted lines 67 in Fig. 7 of the drawings and thus form pockets 68 and intermediate arm portions 69. The pockets are designed to receive the cans which are being fed through the machine. The intermediate arm portions of the discs have arcuate outer faces 70 which are machined to have a running fit with the arcuate inner cylindrical face 71 of the valve housing 32. The pockets 68 will be bounded by solid walls and there will be a complete seal with the valve housing 32 when contiguous arcuate faces 70 are 35 in register with the arcuate inner face 71 of the housing. A passageway 71' extends along the wall and permits a preliminary vacuum action to take place in each pocket as it approaches the main housing. Formed in the wall of the recesses 40 68 are arcuate recesses 72 which receive arcuate 45 ejector fingers 73. These ejector fingers are mounted in the discs 65 and 66 upon shafts 74, the lower end of which shafts extend into thimble bushings 75 while the upper ends of the shafts 74 50 extend through the wall 65 and are fitted with cam arms 76. These arms are secured upon the upper ends of the shafts 74 and swing horizontally. The outer ends of the arms 76 are each fitted with a boss 77 which receives a roller pin 55 78. Carried at the upper end of each of the roller pins 78 is a cam roller 79. These cam rollers travel along a stationary cam groove 80 formed in the under face of the cover member 42 of the valve housing 32. The exact design of the cam 60 groove 80 is indicated in Figs. 6 and 7 of the drawings, where it will be seen that the fingers 73 will lie within the arcuate recesses 72 while a can is being received and carried to the outlet opening 37 of the valve housing 32, at which time 65 the cam arm 76 associated with the pocket 68 within which a can is positioned will be ejected through the opening 37 and into proper engagement with recesses 81 of a star wheel 82. The star wheel is mounted upon a shaft 83 and is 70 driven in synchronism with the shaft 40 of the turret 63 and the shaft 28 of the feed fingers 27.

75 As previously described, the shaft 28 is carried by a bracket 31. By reference to Fig. 4 it will be seen that this bracket is formed with a

tongue 84 which extends in a horizontal groove 85 in the side wall of the valve housing 32. Suitable cap screws 86 hold the bracket in position. The opposite side of the valve housing 32 is formed with a wide throat section 87 which flares outwardly at opposite sides of the opening 37. This throat section terminates in vertical flanges 88 which fit between side flanges 89 carried by a throat plate 90 of the main vacuum chamber housing 38. Clamping members 91 are secured to the flanges 89 by cap screws 92 and overhang the portions 88, thus providing vertical guide-ways within which the portions 88 are held and along which they may move vertically. Packing 15 and clamping members 93 are interposed between the members 91 and 88 and are secured in position by cap screws 94, which make it possible for the entire valve housing 32 to be vertically adjusted and set while accommodating the vertical 20 adjustment of the stretcher through the medium of the adjusting sleeves 54 and 55. It is to be understood that the throat 87 is closed at its upper and lower ends and provides the passage-way 37 with a height somewhat greater than the 25 overall height of the cans which are being fed through it from the recesses 68 in the feed turret 63.

The vacuum housing 38 is a cylindrical structure standing vertically and within which a double seaming feed turret 95 is mounted. The structure is carried on a central vertical shaft 142 and is of the general type shown in my issued U. S. Letters Patent No. 2,052,620 dated September 1, 1936 and entitled "Double seaming machine." That particular structure is characterized as including a series of double seaming heads mounted upon a turret and having upper and lower chucks between which a can and a cap are gripped after they have been loosely clenched together in the unit here indicated at 40 10 in the drawings. The seaming heads include sets of seaming rolls which cooperate to form the initial and final double seaming operations on the cans while the cans are traveling around with the turret and around the axis of the shaft 142. The lower chucks of the seaming turret are indicated at 97 in Fig. 5 of the drawings. It is to be understood that their upper faces are level with the upper face of a floor plate 98 which 45 extends through the throat 87 of the valve housing 32 and is in the same horizontal plane with the upper face of the lower disc portion 66 of the valve turret 65. An arcuate guide rail 99 is disposed above the floor 98 and concentric to the axis of the star wheel shaft 83. This guide rail will direct cans to a point where their longitudinal centers will be concentric with the circular path of travel of the lower chucks 97 and will thereafter be led around with the chucks 50 97, the star wheel 100 and the upper chucks and complementary seaming heads but which operate continuously in producing a double seaming operation as the can passes along the circular path of travel defined by the rotating turret 95.

65 The cans are discharged from the vacuum chamber 39 through a discharge throat 101 communicating with a throat 102 of a valve housing 103. Mounted within the valve housing 103 is a rotating valve element 104 substantially identical 70 with the valve element 63 in the valve housing 32. The rotating element 104 is formed with can pockets 105 into which the cans are fed from the vacuum seaming chamber 39 along a floor 106.

75 Arcuate guide rails 107 extend into the path of

the cans in the double seaming turret 95 and when the chucks of the double seaming turret release the cans the cans are diverted from the turret and on to the floor 106. A star wheel 108 is mounted upon a shaft 109 and is synchronized 5. to feed the cans outwardly along the guide rail 107 and into the pockets 105 of the rotary valve element 104. As previously described for the valve structure including the valve housing 32 and the rotary member 63, the pockets 105 are 10 each provided with an ejector finger 110 which fingers swing around the axis of shafts 111. These shafts carry arms 112 at the free ends of which are cam rollers 113. These rollers travel along a cam groove 114 in the top plate of the 15 housing 103 and function in the same way as the fingers 73, arms 76 and grooves 79 of the inlet can valve.

By reference to Fig. 7 of the drawings it will be 20 evident that the valve housing 103 is provided with vertical adjustment similar to that described for the valve housing 32, the parts being the same in construction and arrangement and herein in being likewise indicated by numerals.

In order to guide the cans into proper engagement with the star wheel 81 and proper travel from the star wheel 108, a guide finger 115 is provided adjacent to the shaft 83 and overhangs the star wheel 81 while a guide finger 116 is mounted adjacent to the shaft 109 and overhangs the star wheel 108.

An outlet opening 117 is formed in the housing 103 and through which the cans are discharged by the fingers 110. A floor 118 is provided level with the floor of the recesses 105 on to which 35 the cans slide. A star wheel 119 mounted upon a shaft 119' carries the cans away from the machine.

The vacuum seaming unit 11 is driven from a suitable line shaft carrying a pulley from which 40 a belt is led to a pulley 120 freely mounted upon a drive shaft 121. The drive shaft 121 stands horizontally and is rotatably supported in a bearing head 122 mounted upon the vacuum chamber housing 38. This head includes a 45 dome portion 123 having a bolting flange 124 through which cap screws 125 extend to engage threaded openings 126 in the upper end of the housing 38. The shaft 121 extends transversely of the vertical center of the bearing head 122 50 and its central longitudinal axis intersects the central vertical axis of the bearing head. Due to the arrangement of the cap screws 125 and the threaded openings 126 it is possible to rotate the bearing head 122 so that the shaft 121 may be 55 disposed in any desired position in a horizontal plane, such for example as the position shown by solid lines in Fig. 2 of the drawings and dotted lines in Fig. 3 of the drawings, or the position shown in solid lines in Fig. 3 of the drawings. 60 Other intermediate angular positions may be assumed if desired in order to properly connect the pulley with the line shaft.

The shaft 121 which carries the pulley 120 also carries the clutch 127 which is manipulated by 65 a shifting yoke 128 and an operating lever 129. The lever 129 and the yoke are connected through a shaft 130 which is mounted in a vertical bearing 131 carried by a bracket 132 secured to the housing 38. The bearing head 122 carries 70 two journal boxes 133 and 134 which are in longitudinal alignment at the top of the bearing head 122 and are spaced from each other. A partition structure 135 connects the contiguous ends of the boxes 133 and 134, and thus provides 75

a grease case, the top of which is closed by a cover plate 136 held in position by cap screws 137. Mounted upon the shaft 121 and within the grease compartment 138 is a bevel gear pinion 139 which is in mesh with a bevel gear 140. The bevel gear 140 is mounted upon the upper end of a vertical drive shaft 142 which extends vertically through the vacuum chamber 39 and the housing 38 and provides a central axis for the 10 double seaming turret 95 referred to previously. The upper end of the shaft 142 is rotatably supported in a bearing 143 which is suspended from the partition 135 of the bearing head 122.

An upper turret drum 144 is mounted upon 15 the shaft 142 directly beneath the bearing 143. This drum has an outer cylindrical wall 145 which is spaced from a cylindrical face 146 of a cooling compartment wall 147 which is within the outer cylindrical wall of the housing 38 and 20 is spaced therefrom to form an annular cooling medium compartment 148, the purposes and advantages of which will be hereinafter explained.

The cooling medium within the compartment 148 will tend to reduce the temperature of the 25 wall 147 and the cylindrical wall 145 of the turret drum 144. This will tend to lower the temperature of spindle bearings 149 which are carried by the turret drum 144 and receive the spindle structures 150 of the double seaming 30 heads 151 which are generally indicated in Fig. 5 of the drawings, and which, as previously described, are of the construction disclosed in U. S. Letters Patent No. 2,052,620 issued to me on September 1, 1936. The spindle bearings 149 are 35 suitably secured to the walls 145 by spiders 152 while the space between the bearings and the shaft 142 is closed by a cup-shaped pan 153. Mounted above the pan 153 is a tubular hub 154 which has a bearing 155 at its lower end through 40 which the shaft 142 extends. The diameter of the tubular hub is such as to cause its cylindrical wall to be spaced from the outer face of the shaft 142 to accommodate a downwardly projecting hub 155 which is carried by the portion 135 of the 45 bearing head 122 and is formed integral with the bearing 143 previously described. The downwardly projecting hub 155 is splined to the member 154 as indicated at 156 so that the member 154 will be held against rotation when in its assembled position. An overhead knocker cam 50 157 is carried at the upper end of the hub 154 and cooperates with the knocker rod 158 in loosening the cans from the chuck in the double seaming heads 151 after the sealing operation.

55 Splined to the shaft 142 is a double seaming center drive gear unit 159 carrying an upper gear 160 and a lower gear 161. The upper gear meshes with the double seaming head drive gears 162 and the lower gear meshes with the double seaming center drive gears 163, one of each such gears being a part of each double seaming head unit 151. The lower end of the upper turret drum 144 is formed with a spider 164 which has a central hub 165. Fitted in the upper end of this 60 hub is an anti-friction bearing 166 having an outer ball race 167 and an inner ball race 168. A lip 169 on the gear unit 159 rests against the inner ball race. A shoulder forming a seat for the outer ball race provides a support for the 65 lower edge of the outer ball race in the hub 165. Disposed beneath the bearing 166 and extending downwardly through the hub is a lower turret sleeve 170. The lower turret sleeve is fastened to the hub 165 by a cap screw 171. Mounted on the lower end of the sleeve 170 is the star wheel 70

100. This is secured to a hub structure 172 by cap screws 173. The cap screws extend downwardly into the end of an adjusting sleeve structure 174. The lower end of the sleeve 170 is fitted with a bearing bushing 175 for the shaft 142. 5 This shaft continues downwardly and extends through the hub of the lower turret 176. This turret receives the spindle structure 177 of the lower chuck plates 97 of the double seaming structure. 10

The lower turret 176 is disposed directly above a transverse spider 178 formed at the bottom of the main housing 38 and there across. An inclined trough is formed around this spider as indicated at 179 and is provided with an outlet 15 opening 180 normally closed by a washer 181. This is held in position by a bolt 182 and a swing nut 183. The lower turret 176 is formed with a central web portion 184 carried by a hub 185. The hub 185 is fastened to a lower sleeve 186 by 20 a suitable fastening bolt 187. The lower sleeve 186 extends downwardly to receive certain driving gears to be hereinafter described. The shaft 142 extends through the sleeve. The upper end of the sleeve 186 carries a suitable bushing 187' 25 for the shaft.

The hub 185 is fitted with an enlarged cylindrical portion 188 at its upper end which is splined within a cylindrical sleeve 189 of the adjustable sleeve structure 174, thus the star wheel 30 100 and the lower turret 176 may have vertical movement with relation to each other while being maintained in driving relation to each other. This adjustment is provided by a compound nut including an outer cylindrical nut member 190 35 40 which is threaded on to a threaded portion 191 of the adjusting sleeve structure 174 at its upper end and to a threaded member 192 at its lower end, which member is secured to the lower turret 176. The threads at the upper and lower ends of the nut 190 are opposite so that rotation of the nut will cause the star wheel 100 and the turret 176 to be drawn towards or away from each other depending upon the direction of rotation. It is preferable that the nut 190 be provided with an outer sleeve 193 which is splined to the nut and which carries a worm gear 194. The worm gear is in mesh with a worm 195 by 45 which the sleeve 193 may be rotated. This rotation will in turn impart rotation to the nut 190 and the worm gear set will hold the nut in a locked position. 50

Disposed beneath the transverse spider portion 178 is the upper wall 61 of the base of the machine. Mounted upon this is the lifting cam 55 196 which cooperates with the lifting rollers 197 of the lower turret spindles in the usual manner. A cam guard 198 is mounted adjacent to the cam 196.

The bed plate 61 is formed with a hub 199 60 which receives a bearing bushing 200 through which the sleeve 186 and the shaft 142 extend. The sleeve 186 projects downwardly a sufficient distance to receive the hub of the lower turret gear 201. The shaft 142 continues downwardly 65 and receives the hub of the lower center pinion 202. The pinion 202 is in mesh with the gear 203 carried upon a stub shaft 204. This shaft is mounted in a suitable bearing on the bed plate 61 and carries a pinion 205 which is in mesh with the gear 201, thus the shaft 142 drives the sleeve 70 187 and the sleeve 170 with the lower turret 176 and the upper turret drum 144.

The various gears are held in their assembled position at the lower end of the sleeve 187 and 75

the shaft 142 by nuts 206. A cap 207 may be secured in place by cap screws 208 at the bottom of the base structure to seal the base housing and also provide access to the nuts 206. Attention is directed to the fact that the base housing which includes the bed plate 61 also includes a gear pan 209 which is secured therebeneath by cap screws 210. The pan 209 encloses other gears of a gear train to be hereinafter set forth.

10 The bed plate 61 carries a bearing 211, upwardly through which extends star wheel shaft 83. This is also held by a bearing 212 adjacent to the floor 98 over which the cans travel into the machine and through the throat 37. The shaft 83 is fitted with a gear 213 which is in mesh with the gear 201 and is driven thereby. A gear 214 is in mesh with the gear 213. The gear 214 is secured to the lower end of the valve shaft 40 and drives the same. In mesh with the gear 214 is a gear 215 which is carried upon the star wheel shaft 28.

15 Disposed at right angles to the position of the star wheel shaft 83 within the vacuum chamber is the star wheel shaft 109. A gear 216 is carried by this shaft and is in mesh with the gear 201. It is to be understood that while not shown in detail in the drawings, the gear 213 with its shaft 83 and the gear 216 with its shaft 109 function alike and are mounted in the same type of bearings and operate in synchronism with the double seaming turret structure to deliver cans to the double seaming turret and to withdraw them therefrom. The gear 216 is in mesh with a gear 217 on the valve 104. This gear is mounted upon the shaft 218 carrying the outlet valve member 104. The gear 217 is in mesh with a final feed gear 219, which is carried by the star wheel shaft 119' and rotates the star wheel 119. It is to be understood that a similar gear train is provided through the unit 10 so that the complete feed of the cans will be brought about in synchronism and so that the cans will be properly delivered to the first star wheel 27 as the cans enter the vacuum double seaming stage.

20 By reference to the arrangement here shown it will be seen that the vacuum chamber 39 is adequately sealed at both ends so that there will be no leak through the various bearings. It is desirable to gain access to the interior of the vacuum chamber from time to time and the various other compartments. As shown in Fig. 7 of the drawings two port holes 220 and 221 are provided in the wall of the housing 38. These are substantially at right angles to each other and the central axis of the housing. Each of these openings is fitted with cover plates 222, here shown as pivotally mounted at 223 to a clamping lever 224. The levers 224 are pivoted at 225 to the housing and are secured in place by clamp bolts 226. Suitable gaskets 227 are interposed between the cover plates 222 and the end faces of the walls of the housing surrounding the two port holes. It may also be desirable to gain access to the lubricating space within the head 122. A cover structure for this purpose is indicated at 228 in Fig. 5 of the drawings.

25 Under various circumstances it is desirable to place the vacuum closing machine at a particular level with relation to the flow lines and the delivery tables, and this is especially so when the machine is adjusted for cans varying in height since the present machine provides that the lower mechanism shall be raised in order to adjust the machine to short cans and shall be lowered in order to adjust the machine to tall cans. This

adjustment is accomplished as previously described by the adjusting units associated with the shafts 40 and 218 of the inlet and outlet valves, as represented by the sleeves 54, 55 and 60 shown in Fig. 4 of the drawings and the adjustment for the lower turret represented by the nut 190 and the members 191 and 192 shown in Fig. 5 of the drawings. When such adjustments have been made it is necessary to move the machine bodily. This is accomplished by providing the bed plate 61 with legs 229. The legs are bolted beneath portions of the bed plate 61 by cap screws 230 and extend downwardly. The lower ends of the legs 229 have an outwardly flaring canopy 231 for a purpose to be hereinafter described. A central opening is formed upwardly through each of the legs and at the lower end of each of such openings a threaded bushing 232 is secured. Extending through the threaded bushing is the threaded portion of an adjustable leg rod 233. The upper ends of these rods project above the upper level of the bed plate 61 and as shown in Fig. 2 of the drawings have squared portions 234. The lower ends of the rods are each fitted with a bevel gear 235 which is secured in place upon the rod beneath the threaded bushing 232, in fact the bushing rests directly against the upper end face of the hub of the bevel gear. The gear is formed with a hub portion 235 having an enlarged outwardly flaring canopy with a downwardly extending cylindrical wall 236. Extending upwardly into the mouth of this member is a foot piece 237 which rests upon the floor and has an upper seat to receive an anti-friction bearing 238 which is interposed between the foot piece 237 and the canopy 236. The foot piece is secured to the lower end of the rod 233 upon which it is mounted by a nut 239. Thus, it will be recognized that when the leg structure is assembled, as here shown and described, the weight will be imposed upon the bearing 238 and that when the shaft 233 is rotated through the threaded bushing 232 the leg 229 will be in effect lengthened or shortened in order to position the adjusting mechanism at a proper operating level.

30 It is desirable that the legs 229 shall be simultaneously adjusted for length. They are, therefore, all operatively connected. Formed on the side of each of the legs 229 is a bearing bracket 240 within which a shaft 241 is rotatably supported. At each end of each of the shafts 241 a bevel gear pinion 242 is secured. These pinions are in mesh with the bevel gears 235 carried by the leg rods 233. It is to be understood that the gear shafts 241 are disposed between legs of the structure and that they carry pinions 242 at their opposite ends in mesh with the gears 235 of the leg structures between which they extend. By this arrangement when one of the leg shafts 233 is rotated rotation will be imparted through the gear shafts 241 to the other shafts 233 so that they will rotate simultaneously in a raising or lowering operation.

35 A wrench 243 is provided, as shown in Fig. 6. It is formed with a handle and a head. The head 65 has a squared opening 244 through it to receive one of the upper extending squared portions 234 of a leg rod 233. It will be evident that since each of the leg rods is supplied with a member 234 it is possible for the handle to be used at 70 the most convenient location around the machine.

40 By reference to Figs. 1, 3 and 11 it will be seen that the valve units comprising the inlet feed valve 29 and the discharge valve structure 103 75

are hinged for horizontal swinging movement upon the main housing of the vacuum seaming machine. Here it will be seen that hinges 250 are provided to support the valve units and to permit them to swing away from the side faces of the housing 38 with which they form a seal. Locking lugs 251 are disposed upon the opposite sides of the housings 32 of the two valve units and are engaged by locking bolts 252 which are pivoted to the housing upon pins 253 and provided with lock nuts 254, as particularly shown in Fig. 3 of the drawings. It will be recognized that in this type of valve unit construction the valve units are fixed so far as vertical adjustment is concerned.

Referring more particularly to Fig. 11 of the drawings, it will be seen that the valve housing 32 is cylindrical and that its inner face 255 is preferably tapered downwardly and inwardly. This insures a tight seal between the lower disc 66 of the turret 63 and between the upper disc 65 of the turret and the inner surface of the housing. The upper end of the housing is closed with a cover plate 42, as previously described, and the lower end of the housing is closed by a spider 50.

The shaft 40 which extends through the turret 63 is shown in Fig. 11 of the drawings as being formed at its upper end with a transverse slot 256 through which a tapered pin 257 extends. The pin 257 also extends through the walls of a hub 258 formed as a part of the turret 63. The upper end of the shaft 40 is formed with a central counter-bore 259. This counter-bore receives an adjusting pin 260 through which the tapered pin 257 also passes. The upper end of the adjusting pin is provided with lock nuts 261 by which the vertical position of the turret 63 on the shaft 40 may be set. The upper end of the shaft 40 is provided with a lock nut 262 which rests against the inner race of the anti-friction bearing 41. By this arrangement it is possible to adjust the tapered faces of the upper and lower turret discs with relation to the tapered face of the housing 32. The shaft 40 is fitted at its lower end with the gear 214 which is in mesh with the other gears in the gear train. This gear is suitably driven by a shaft 263 which is in longitudinal alignment with the shaft 40 and therebeneath. Mounted upon the shaft 263 is a safety clutch element 264 which is pinned to the shaft, the element 264 having a transverse keyway 264' in its upper face to receive a key 265' formed on the under side of a disc 265. Disposed above the disc 265 is a disc 266 having a key 266' on its upper face to engage a keyway 267 formed as part of a disc 268 and running transversely but perpendicular to the slot 264' and a key 268' formed on its upper face. The key 268' engages a keyway 269 formed in the under side of the gear 214. In alignment with the keyways 267 and formed in the under face of disc 268 and in the upper face of disc 265 and in alignment with each other are slots 269' and 270 to receive a pin 270' which holds the complete unit in assembled relation. The structure thus is built to enable the operator to quickly swing out the turret 29. This is done by pulling the pin 270' and sliding out the disc 265 on its key 265'. The two structures are thus disengaged.

In operation of the present invention it is assumed that cans are flowing into the machine from various can runways and that they are delivered to the machine on a predetermined horizontal plane. The cans are led onto the floor

of the feed structure and into engagement with the star wheel 12, after which they are led around the tracks 13 and 14 and between tracks 16 and 17, where they are fed forwardly by the star wheel mechanism 15. The cans are then delivered to the arcuate runway defined by the rails 18 and are fed forwardly by suitable feed means 18'. The cans are then led through the unit 10 where the caps are loosely crimped to the body of the can. Here they are engaged by suitable crimping heads 21 and are led around the turret 19, after which they are discharged by the star wheel 22 along the rail 24 and to the transfer disc 25. The transfer disc is at a predetermined level and it is therefore necessary to adjust the floor 26 of the vacuum double seaming unit 11 to accommodate the can, regardless of the height of the can. The initial adjusting action in order to accommodate cans of various heights is made in the vacuum double seaming unit.

By reference to Fig. 5 it will be seen that the upper turret 144 of the double seaming unit carrying the double seaming heads is supported in the housing 38 in a manner to preclude the possibility of vertical adjustment. It is necessary, therefore, to adjust the upper turret structure, including drum 144 and head 151 to lower it toward the lower chuck plates 97 to a desired level. This is accomplished by rotating the threaded adjusting sleeve 190 which acts to telescope the structure including the members 191, 192 and the sleeve 190 and will draw the lower turret frame 176 upwardly while at the same time lifting the lower chuck plates 97. As the lower turret structure 176 is lifted the hub 185 with its extension 188 will slide upwardly on the shaft 142 and within the sleeve 174. Since the portions 174 and 188 are splined together it is evident that a driving connection will be maintained for the spider 100 and the lower turret 176 irrespective of the adjustment. The adjusting rotation of the threaded sleeve 190, as previously set forth, is brought about by rotation of a worm 195 which is in mesh with a worm gear 194 carried by the lower turret 176 in a bearing 195'. The bearing is provided with a suitable lock screw 196' by which the structure may be held in its locked position. It will be seen that as the upper turret including the drum 144 and head 151 are lowered they will reduce the space between the lower chuck plates 97 and the chuck plates in the seaming heads 151 to accommodate a shorter can. If required, the intake valve housing 32 and the outlet valve housing 103 may be adjusted by means of the threaded sleeve 55 shown in Fig. 4 of the drawings and the cooperating action between this sleeve and the members 54 and 60. Thus, it will be seen that the valve housings with their entire feed mechanisms may be adjusted until the upper face of the floor 66 of the rotating valve elements 63 and 104 are in horizontal alignment with the floor 98. The valve housings during such an adjustment slide vertically in the guide structures 65 comprising the members 89 and 90 and the members 91, as shown in Fig. 7. When the valve housings have been placed at the desired height or level they are set in position by the set screws 94. Suitable gaskets 83' are interposed between the faces 88 of the valve housings and the face of the main housing 38, as shown in Fig. 5 of the drawings. This insures a vacuum seal across the upper and lower edges of the valve housings while the clamping action of the bolts 75

94 to bring the faces of the members 88 and 90 together will seal the joint vertically.

When these adjustments have been completed it will be evident that the feed plane of the inlet valve structure is out of alignment with the plane of the transverse disc 25. It is then necessary to bodily adjust the machine vertically. This is done by applying the wrench 243 to one of the extensions 234 of the leg rods 233. Appropriate rotation of the rod to which the wrench has been applied will cause simultaneous rotation of all of the other rods 233, here shown as being four in number. After the machine has been thus vertically adjusted the clenched cans are passed from the transfer disc to the star wheel 27 and are then fed into the housing 32 and into the pockets 68 of the rotary valve member 63. While the cans are thus fed into the pockets which come to register with the inlet opening 36 of the housing 32 the ejector fingers 73 will lie with their outer faces flush and conforming with the contour of the recesses 68 into which the cans are placed.

As the cans pass around within the housing 32 and while carried by the rotary valve element 63 the cam rollers 79 will travel along the cam groove 80 and will act upon the levers 76 so that as the can reaches the outlet throat 37 of the inlet valve housing 32 the ejecting fingers 73 will swing outwardly to move the can through the throat 37 and on to the floor 98. Here it will be engaged by the star wheel 82 and carried into the double seaming machine. During the double seaming operation there is a tendency for the seaming head structure and its bearings to overheat. This is due to the fact that the entire operating mechanism is hermetically enclosed within the housing 38 and that a condition of partial vacuum exists. In order to maintain the working parts at a suitable temperature a cooling liquid is circulated within the cooling chamber 148. It has been found that water drawn directly from the commercial water lines of a plant is sufficient. A water line is, therefore, attached to a connection 245, as shown in Fig. 2 of the drawings. This introduces water at a relatively low temperature to the compartment 148 at one side of a vertical partition wall 246. The water is then free to circulate around and within the compartment 148 and to be discharged therefrom through an outlet opening 247, here shown as disposed near the top of the chamber 148 and upon the opposite side of the partition wall 246 from the inlet opening 245. This cooling medium absorbs the heat carried by the upper turret drum 144 and in actual practice maintains the structure sufficiently cool for proper operation.

A connection to a suitable suction pump is attached at 249 and leads through a passageway 250 into the vacuum chamber 39.

After the cans have been seamed they are transferred from the double seaming head by the star wheel 108 to the outlet valve housing 103, where they are delivered into the pockets 105 of the rotary valve element 104. Upon reaching the outlet throat 117 of the valve housing 103 the cans are ejected from their respective pockets by the ejector fingers 110 and are delivered onto the table 118, where they are fed forwardly by the star wheel 119.

It will thus be seen that the vacuum double seaming machine here disclosed is simple in its construction, since it does not require the use of specially designed cap feed mechanism or specially designed double seaming mechanism, and pro-

vides means whereby double seaming mechanism of standard design may be used satisfactorily within a completely enclosed vacuum chamber without over-heating. It will further be noted that the valve mechanism is simple and direct in its action in receiving and ejecting cans, and that the entire machine may be quickly adjusted without the removal or replacement of parts to accommodate cans of various heights, and that when desired the machine may be easily adjusted to accommodate cans of various diameters.

While I have shown the preferred form of my invention as now known to me, it will be understood that various changes may be made in combination, construction and arrangements of parts by those skilled in the art, without departing from the spirit of my invention as claimed.

Having thus described my invention, what I claim and desire to secure by Letters Patent is:

1. A rotary double seaming machine for cans comprising a vertical drive shaft, an upper turret moving around the axis of said shaft, double seaming heads carried by said turret, a lower turret rotating around the axis of said shaft and supporting cans to be seamed, a frame rotatably supporting the shaft, driving connections between the shaft and the turrets, a driving connection between the lower turret and the shaft, a driving connection between the lower turret and the upper turret, and adjustable means interposed in the last named driving connection whereby the two turrets may be set in a desired spaced relation to each other.

2. A vacuum double seaming machine comprising a can double seaming unit, a vacuum housing enclosing the same, said housing having openings in the side thereof, one through which cans are introduced into the housing and the other through which they are withdrawn, a can valve for each of said openings and by which the vacuum seal is maintained within the housing while introducing the cans into the housing and withdrawing them therefrom, means associated with the can valves and acting to move the cans from within the housing of the can valve structure, means for changing the level of the plane along which the bottom of the cans move while within the housing, and means for adjusting the can valve structures to dispose the lower ends of the cans in the plane assumed by them within the vacuum chamber.

3. In a device of the character described, the combination with a vacuum housing having an opening in the side wall thereof, a valve housing having openings in the side wall thereof, one of said openings providing an inlet passageway for cans and the other of said openings providing a passageway for cans from the valve housing to the vacuum housing, a rotary valve element within said housing, the contiguous faces of the valve element and the housing having a running fit, can receiving pockets formed in the periphery of the rotary valve element, swinging arms, one within each of said pockets, and overhead control means for said arms acting to move the arms to an unobstructing position when the cans are introduced into the pockets and are moved therewith within the valve housing and to an ejecting position when the cans and pockets move to register with the opening leading from the valve housing into the vacuum housing.

4. In a device of the character described, the combination with a vacuum housing having an opening in the side wall thereof, a valve housing having openings in the side wall thereof, one of

- said openings providing an inlet passageway for cans and the other of said openings providing a passageway for cans from the valve housing to the vacuum housing, a rotary valve element with-
5 in said housing, the contiguous faces of the valve element and the housing having a running fit, can receiving pockets formed in the periphery of the rotary valve element, swinging arms, one within each of said pockets, overhead control means for
10 said arms acting to move the arms to an unob- structing position when the cans are introduced into the pockets and are moved therewith within the valve housing and to an ejecting position when the cans and pockets move to register with
15 the opening leading from the valve housing into the vacuum housing, and means for vertically ad- justing the position of the valve housing and the rotary valve element with relation to the vacuum housing.
20 5. In a device of the character described a housing forming a vacuum chamber within which cans are to be double seamed and which housing is in communication with suction creating means, said housing having an opening through which
25 cans are passed to the chamber, a valve housing disposed in proximity to the first named housing and having an opening in communication with the opening through the first named housing and through which cans may pass, the valve housing
30 being formed with a second opening through which cans enter the valve housing, a rotary valve ele- ment within the valve housing forming a sub- stantially air-tight seal with the housing, a plu-
35 rality of can receiving pockets in said rotary element into which cans are placed and from which they are discharged into the housing of the vac- uum chamber, and a conduit extending along the wall of the valve housing and in communication with the vacuum chamber whereby a vacuum ac-
40 tion will be created within a pocket of the rotary member as it advances toward the point of dis- charge of the can within said pocket into the vacuum chamber.
6. A vacuum double seaming machine includ-
45 ing a main housing, a double seaming unit within said main housing and which main housing is under a condition of partial vacuum, inlet and outlet openings in the side walls of said housing through which cans may pass, can valve units
50 disposed over said openings and through which cans are fed to the main housing and withdrawn therefrom without breaking the seal of the hous- ing, hinge means for supporting said valve units on the housing whereby the valve units may swing

toward and away from operative positions with relation to the openings in the main housing, driving means for the valve units, and interlock- ing driving connections between the driving means and the valve units whereby the valve units 5 may be swung bodily out of engagement with the driving means.

7. A rotary double seaming machine including a central vertical shaft, a turret mounted thereon and rotating around the axis thereof, said turret 10 including double seaming heads, a gear train disposed at the upper end of the turret for driv- ing the same and said heads, a cylindrical housing for the gears carried by and moving with the turret, and a stationary circumscribing water 15 jacket for said housing with its inner circum- ferential wall in close proximity to the outer sur- face of said turret gear housing whereby heat radiation will take place from the turret gear housing to the water jacket as the turret rotates. 20

8. In a double seaming machine, a vertical shaft, an upper turret and a lower turret mounted thereon, can supporting chucks on the lower tur- ret, seaming heads on the upper turret, a splined connection between the upper turret and the low- 25 er turret and a threaded coupling between the upper turret and the lower turret whereby said turrets may be vertically adjusted with relation to each other.

9. Same as 8, adding the following:—and an 30 irreversible gear structure for rotating and set- ting said threaded coupling.

10. A supporting structure for double seaming machines and the like, including a sub frame having leg elements disposed at points around 35 the bottom thereof, vertical bores in said legs, threaded bushings, one secured in each of said vertical bores, screws, one for each of said thread- ed bushings, said screws being fitted with a foot at their lower ends, gears, one splined on each 40 of said screws and being disposed between the threaded bushing and the foot to dispose the weight of the sub frame on the foot and gearing in engagement with the several gears of said screws and adapted to be simultaneously driven 45 thereby to rotate the screws with relation to the threaded bushings and to raise or lower the sub frame.

11. Same as 10, adding the following:—and anti-friction bearings interposed between the 50 gear structures and the feet to facilitate rotation of the gears.

HENRY L. GUENTHER.
